UNITED STATES PATENT OFFICE.

ROBERT AMORY, OF MILTON, MASSACHUSETTS, ASSIGNOR, BY MESNE ASSIGNMENTS, TO THE LAMSON COMPANY, OF SYRACUSE, NEW YORK, A CORPORATION OF MASSACHUSETTS.

SWITCHING MECHANISM FOR CONVEYER SYSTEMS.

Application filed March 22, 1922. Serial No. 545,702.

To all whom it may concern:

Be it known that I, ROBERT AMORY, a citizen of the United States, residing at Milton, in the county of Norfolk and State of Massachusetts, have invented certain new and useful Improvements in Switching Mechanism for Conveyer Systems, of which the following is a specification.

This invention relates to conveyer systems which have diverging paths or ways along which the carriers or articles being conveyed are conducted and which also include automatic mechanism for switching the carriers from one of said ways into another. The invention is especially concerned with the general type of conveyer system disclosed in my prior application Serial No. 487,334, filed July 25, 1921, which includes an automatic switching apparatus of a novel character for controlling the path of travel of the carriers.

It is the chief object of the present invention to devise a switching or diverting mechanism of the general type above mentioned which will operate accurately and positively when the carriers are spaced apart on the conveyer by relatively short distances. The invention also aims to improve and perfect the apparatus shown in my prior application with a view to rendering it more rapid in operation, to increasing the carrying capacity of the system, and simplifying the construction of the switching means.

The nature of the invention will be readily understood from the following description when read in connection with the accompanying drawings, and the novel features will be particularly pointed out in the appended claims.

Referring now to the drawings,

Figure 1 is a plan view of an apparatus constructed in accordance with the present invention;

Fig. 2 is a cross sectional view on the line 2-2, Fig. 1;

Fig. 3 is a side elevation of the apparatus shown in Fig. 1;

Fig. 4 is a plan view showing another embodiment of the present invention;

Fig. 5 is a view, somewhat diagrammatic, showing the arrangement of one of the switching units included in the apparatus shown in Fig. 4;

Fig. 6 is a view similar to Fig. 5 of another of the switching units shown in Fig. 4; 55

Fig. 7 is a plan view of the controller arm used in Fig. 6; and

Fig. 8 is a plan view of the switch shown in Fig. 6.

Referring first to Figs. 1, 2 and 3, the construction there shown comprises a conveyer belt 2 supported on a series of rolls 3 which are mounted between angle irons 4-4 that are supported by suitable standards. The belt travels in the direction indicated by the arrow, Fig. 1, and it may be driven in any convenient manner. Diverging from the conveyer belt 2 is a roller conveyer 5 of known construction, this conveyer forming a station into which certain of the carriers being conveyed are diverted. Before the carriers reach the switching point they pass through an automatic spacing mechanism, indicated in general at D, Fig. 1, which spaces them apart along the conveyer belt by at least certain minimum intervals. This spacing mechanism forms the subject matter of a copending application. 75

The carriers handled by this conveyer system consist, in the present instance, of boxes C, Fig. 3. One end of each carrier C is bevelled or inclined, as shown at 7, Fig. 3, and the carriers are placed on the conveyer belt with their square ends forward if the carriers are full, and with their bevelled ends forward if they are empty. Each box is marked with the words "Full" and "Empty" associated with arrows, as shown in Fig. 3, to aid the workman or attendant in placing the boxes or carriers properly on the conveyer. This difference in the end construction of each carrier is utilized in performing the automatic switching operation. 80

For the purpose of diverting certain of the carriers C from the belt 2 onto the branch conveyer or station track 5, a switch 10 is located at the junction of these two conveyer units. This switch is pivoted on a post 12 mounted at one side of the conveyer belt 2 and is inclined toward the belt so that the switch normally is held by gravity in its diverting or switching position, as shown in Fig. 1. A stop 13, Fig. 3, limits the swinging movement of the switch. Normally when one of the carriers C strikes the switch, it is swung by the carrier out of the 95 100 105

path of movement of the carrier and allows the carrier to proceed along the belt. The switch then returns by gravity to its initial position.

5 In order to lock the switch in its switching position when desired, an automatic controlling mechanism is provided which is arranged to be operated by the carriers just before they reach the switch. This mechanism 10 comprises a controller arm 14 overlying the belt 2 and pivoted in the upper end of an upright post 15 to swing in a substantially vertical plane. The post is mounted in suitable bearings to turn about 15 its own axis. The controller arm is free to swing in a vertical plane without affecting the post, but when subjected to horizontal pressure turns in a horizontal plane turning the post with it. If a full carrier 20 travelling with its square end foremost strikes the controller arm, it swings the arm and the post 15 about the axis of the post, and this movement is transmitted through a link 16, Fig. 3, to a lever 17 on which rests 25 a block 18 carrying an upright pin 19 that projects through one of the angle bars 4. These connections thus operate at this time to raise the pin 19 into a position immediately behind the free end of the switch 10 30 where it locks the switch in its operative or switching position. Consequently, when the carrier strikes the switch 10, it is diverted by said switch onto the roller conveyer or station track 5. A coiled spring 35 20, Fig. 1, returns the post 15 and the controller arm 14 to their initial positions. When an empty box strikes the controller arm 14, its bevelled end 7 lifts the arm but this movement is not transmitted to the 40 locking pin 19. Consequently, the switch 10 is left unlocked and the carrier therefore opens the switch and proceeds uninterrupted along the belt.

It will now be apparent that this mechanism 45 automatically switches or diverts the full boxes but does not divert the empty boxes or carriers. When the station 5 becomes filled with full boxes, the switching mechanism is rendered inoperative to switch 50 or divert further boxes into the station, and for this purpose a bell crank lever 22 is mounted just below the conveyer 5 with one end projecting into position to be struck by each carrier immediately after it has 55 entered the station. This lever is connected by a link 23 with one end of a bell crank lever 24, Fig. 3, the other end of which is connected to the lower end of a rod 25 which extends upwardly immediately beside the 60 post 15. The upper end of this rod projects through a slot 26 formed in the controller arm 14, and it is provided with a head 27 that overlies the upper edge of this slot. The carrier that completes the filling of the 65 station 5 rests on the lever 22, and as it

strikes this lever it operates through the connections just described to tip the controller arm 14 into its raised position where it is entirely out of the path of travel of the carriers as they move along the belt. 70

The end of the arm 14 which overlies the belt is weighted, and the weights of the other parts are so disposed that as soon as the carrier which holds the lever 22 depressed rolls down the track out of contact 75 with the lever, the parts will immediately return by gravity to their normal positions, as shown in Figs. 1, 2 and 3. Obviously springs could be employed to perform this function and also to return the switch to 80 its normal position. It is preferred, however, to use gravity for this purpose in most instances since it simplifies the construction.

In the arrangement shown in Figs. 1, 2 and 3, boxes or carriers which are small enough to pass under the controller arm will not be diverted, regardless of whether they are full or empty, and these boxes will simply open the switch 10 and travel along the conveyer belt 2. Under some circumstances it is desirable to have these small boxes switched on to a branch track or station. It is also desirable under some circumstances to keep the switch normally locked. A switching mechanism designed 95 to fulfill these requirements is illustrated in Figs. 4 to 8 inclusive.

Referring first to Figs. 4 and 5, the switch 30 is essentially like the switch 10, above described, and is mounted on an inclined 100 pivot or post 31, (the inclination of the post not appearing in the illustration) so that it normally is held by gravity in its switching position, a stop 32 limiting the movement of the switch under the influence of 105 gravity. The switch is normally locked in this position by a locking lever 33 which is pivoted at 34 and has a weight 35 on one end thereof tending to hold it in its switch locking position. A chain 36 and a link 37 connect the lever 33 with one arm of a bell crank lever 38, the other arm of which is connected by a link 39 to an arm 40 pinned on a post 41 which is mounted to turn and has its upper end bent into a horizontal position, as shown at 42, where it constitutes 110 a controller arm corresponding in certain functions to the controller arm 14 above described.

With this arrangement the boxes or carriers small enough to pass under the arm 42 will be diverted by the switch 30 onto the branch conveyer or station track 43. Either full or empty carriers of the larger size, however, will strike the controller arm 125 42 and swing it, this movement being transmitted through the connections with the lever 33, thus rocking the lever in a clockwise direction, Fig. 5, far enough to unlock the switch 30. These carriers, conse- 130

quently, are permitted to swing the switch into its open position and travel uninterruptedly along the conveyer belt 2.

After passing the switch 30 the carriers 5 approach another switch 45, see Figs. 4 and 6, which is pivoted on an inclined post 46, (the inclination of which is not shown in the drawings) so that it normally lies across the belt 2 in position to divert the carriers 10 into an inclined chute 47. A stop 48, Fig. 6, limits the swinging movement of the switch under the influence of gravity. Normally the switch is held locked by a locking lever 49 supported and mounted in the same 15 manner as the lever 33, above described, and connected by a chain 50 and link 51 with a bell crank lever 52. This lever is connected by a link 53 with another bell crank 54 which has a pivotal connection with the lower end of an upright rod 55 mounted immediately beside the post 46. The post 46 is mounted to turn about its own axis, and a controller arm 56 is pivoted in the upper end of the post 46 for up and down movement but is compelled to turn with the post. This controller arm, its connection with the post 46, and the mounting of the post, are the same as those above described in connection with Figs. 1, 2 and 3. The upper 20 end of the rod 55 projects through a curved slot 57 formed in the controller arm 56, and the controller arm bears on a collar 58 secured to the rod 55.

An empty carrier of the construction 35 shown in Fig. 3, upon approaching the switch 45, will strike the controller arm 56, and the bevelled end 7 of the carrier will tip the arm, thus operating through the connections with the locking lever 49 to release the switch. Such a carrier, therefore, 40 will immediately strike the switch, open it, and continue its travel along the belt 2. A full carrier, however, upon striking the controller arm 56 will simply turn this arm 45 and the post 46 about the axis of the post but will not release the lock 49. Consequently, this carrier will be diverted into the chute 47. In this arrangement also the boxes small enough to pass under the controller arm 56 will be diverted into the 50 chute assuming, of course, that they have not already been diverted by a switch.

It will now be appreciated that this invention provides a very simple form of automatic diverting mechanism, the essential 55 features of which are readily adaptable to a variety of conditions. The various parts of the mechanism are of such rugged construction that there is very little liability 60 of their failing to function properly. Inasmuch as the switch is controlled by a device located immediately in front of it, and since for certain conditions the switch is not required to open, it will operate satisfactorily even when the carriers are spaced

at relatively close intervals on the belt. This fact is of great practical importance for the reason that the closer the carriers can run and still have the switching mechanism function properly, the greater is the 70 effective carrying capacity of the conveyer.

It will also be understood that while I have herein shown and described the best embodiment of the invention of which I am at present aware, it may be modified in 75 many particulars without departing from the spirit or scope of the invention.

Having thus described my invention, what I desire to claim as new is:

1. In a conveyer system having diverging 80 ways for carriers, the combination of a switch for diverting carriers from one of said ways into another, and controlling mechanism for said switch comprising a device constructed and arranged to be struck by the carriers before they reach said switch and to be moved alternatively in planes substantially at right angles to each other by the carriers according to the part of the carrier engaging said device. 90

2. In a conveyer system having diverging 95 ways for carriers, the combination of a switch for diverting carriers from one of said ways into another, controlling mechanism for said switch comprising a device constructed and arranged to be struck by the carriers before they reach said switch, said device being arranged to swing alternatively about a substantially horizontal or a vertical axis when engaged by carriers of 100 different configuration, utilizing certain only of said movements of said device to affect the operation of the switch.

3. In combination with a conveyer system 105 comprising a substantially straight uninterrupted main track and a branch track diverging therefrom, a pivoted switch device normally positioned to deflect bodies moving along the conveyer from their normal path along the main track, releasable means acting upon the free extremity of the switch device for positively retaining said device in normal position, and means actuatable by an indicator carried by a body approaching 110 along the conveyer for determining release of said retaining means. 115

4. Switch mechanism for use with a conveyer track having a substantially straight uninterrupted main portion and a branch portion diverging from an intermediate part of the main portion comprising a movable switch member normally extending across the main portion of the track for compelling bodies moving along said main portion to diverge laterally therefrom onto the branch, 120 releasable means positively retaining such switch member in normal position, and means comprising an element supported independently of said switch member and actuatable by an element of a body moving 125 130

along said track for determining release of such retaining means.

5. Switch mechanism for use with a conveyer having a substantially straight uninterrupted main track and a branch track diverging from an intermediate point in the main track comprising a pivotally supported switch member normally extending diagonally across the main track, releasable switch means positively retaining said member in normal position, and feeler means comprising an element supported independently of said switch member and engageable with an element of a body moving along said track for determining release of said member by the retaining means.

6. In a conveyer system having diverging ways for carriers, the combination of a switch normally in position to divert carriers from one of said ways into another, said switch being mounted to be moved out of said position by the carriers, means for locking said switch in its normal position, and mechanism for operating said locking means including a controller arm mounted in the path of movement of the carriers before they reach said switch, said arm being mounted for movement in different directions, and connections between said arm and said locking means for transmitting certain movements of the arm to said means but inoperative to transmit other movements of said arm to said means.

7. In a conveyer system having diverging ways for carriers, the combination of a switch normally in position to divert carriers from one of said ways into another, said switch being mounted to be moved out of said position by the carriers, means for locking said switch in its normal position, mechanism for operating said locking means including a controller arm mounted in the path of movement of the carriers before they reach said switch, said arm being mounted to tip up and down and to swing in a substantially horizontal plane, and connections for transmitting one of said movements to said locking means to operate it but incapable of so transmitting the other of said movements.

8. In a conveyer system having diverging ways for carriers, the combination of a switch normally held across one of said ways in position to divert carriers therefrom into another way, supporting means for said switch permitting it to be moved out of said position by said carriers whereby they are allowed to continue along the first way, a lock for holding said switch in said normal position, a controller arm in the path of travel of the carriers before they reach said switch, means supporting said arm to tip up and down and to swing in a substantially horizontal plane when struck by a carrier, and connections between said arm and lock

for utilizing one of said movements to operate the lock.

9. In a conveyer system having diverging ways for carriers, the combination of a switch normally held across one of said ways in position to divert carriers therefrom into another way, supporting means for said switch permitting it to be moved out of said position by said carriers whereby they are allowed to continue along the first way, a lock for holding said switch in said normal position, a controller arm in the path of travel of the carriers before they reach said switch, means supporting said arm to tip up and down and to swing in a substantially horizontal plane when struck by a carrier, connections between said arm and lock for utilizing one of said movements to operate the lock, and additional connections arranged to be operated by the carriers on one of said ways for moving said arm into a position out of the path of travel of said carriers.

10. In a conveyer system having diverging ways for carriers, the combination of a switch normally held across one of said ways in position to divert carriers therefrom into another way, supporting means for said switch permitting it to be moved out of said position by said carriers whereby they are allowed to continue along the first way, a lock for holding said switch in said normal position, a controller arm in the path of travel of the carriers before they reach said switch, a substantially upright post on the upper end of which said arm is pivoted for up and down movement, means supporting said post to turn about its own axis, and connections between said lock and post whereby the turning movement of the post actuates said lock.

11. In a conveyer system, the combination of a main conveyer for carriers, a branch conveyer diverging from said main conveyer, a switch normally lying across said main conveyer in position to divert carriers therefrom onto said branch conveyer, supporting means for said switch permitting it to be moved out of said position by the contact therewith of said carriers whereby the carriers are allowed to continue along said first conveyer, a lock for holding said switch in said normal position, a controller arm in the path of travel of said carriers before they reach said switch, and connections between said arm and lock for utilizing the movement of said arm by said carriers to operate said lock.

12. In a conveyer system, the combination of a main conveyer for carriers, a branch conveyer diverging from said main conveyer, a switch normally lying across said main conveyer in position to divert carriers therefrom onto said branch conveyer, supporting means for said switch permitting it

to be moved out of said position by the contact therewith of said carriers whereby the carriers are allowed to continue along said first conveyer, a lock for holding said switch in said normal position, a controller arm in the path of travel of said carriers before they reach said switch, means supporting said arm for swinging movement when struck by one of said carriers, means for returning said arm to its initial position after it has been moved away from said position by a carrier, and connections between said arm and lock for utilizing the movement of said arm to operate the lock.

15 13. A conveyer system including a conveyer for carriers, a station comprising a track diverging from said conveyer, automatic means for switching carriers into said station, and automatic mechanism for rendering said switching means inoperative to divert carriers into said station when the station is full, said mechanism including a device arranged to be engaged by the bottom of a carrier that completes the filling of said station.

14. In a conveyer system, the combination of a main conveyer for carriers, a branch conveyer diverging from said main conveyer, a switch for diverting carriers from said main conveyer on to said branch conveyer, controlling mechanism for said switch including a controller arm in the path of travel of said carriers before they reach said switch, supporting means for said arms permitting it to tip up and down and to swing in a substantially horizontal plane when struck by a carrier, a device arranged to be engaged by the bottom of a carrier on said branch conveyer, and connections between said device and said arm for moving the arm out of the path of travel of the carriers on said main conveyer, whereby when said device is actuated by a conveyer it will hold said arm in an inoperative position.

15. In a conveyer system, the combination of a main conveyer for carriers, a branch conveyer diverging from said main conveyer, a switch normally lying across said main conveyer in position to divert carriers therefrom onto said branch conveyer, supporting means for said switch permitting it to be moved out of said position by the contact therewith of carriers whereby such carriers are allowed to continue along said first conveyer, a lock for holding said switch in said normal position to divert carriers into the branch track, and means for releasing the lock actuatable by selected carriers on said main conveyer before they reach the switch.

16. Switch mechanism for use with a belt conveyer having a substantially straight main track provided with a moving floor, and a branch track diverging from the main track, comprising a movable switch member

arranged adjacent to the junction of said diverging track, means normally locking the switch member in position to divert carriers onto the branch track with the main track, and means actuatable by a body approaching along the main track automatically to determine release or retention of said switch member by the locking means.

17. A conveyer having a main track and a branch track, a switch bar normally extending across the main track in position to divert bodies approaching along such track into the branch track, and releasable means acting upon the free extremity of the bar for positively holding it in such position, said bar, when released from said holding means, being movable from across the main track by direct contact of an approaching body therewith.

18. A conveyer having a main track and a branch track, a switch bar pivotally supported at one side of the main track and normally extending transversely across the same, and releasable means acting upon the free extremity of the bar for holding the latter in such position, said bar being swingable into substantial parallelism with the main track by impact of a body moving along the main track when such bar is released from the holding means.

19. Switch mechanism for use in a conveyer having a main track provided with a moving floor and a fixed track diverging from the main track comprising a movable switch member arranged adjacent to the junction of said diverging track with the main track and means comprising an element supported independently of said switch member and actuatable by a body approaching along the main track automatically to determine movement of said switch member by engagement therewith of such approaching body.

20. Switch mechanism of the class described comprising a switch bar pivotally supported adjacent to one of its ends, latch means associated with the opposite end of the bar for retaining it in predetermined position, a movable feeler, and means operable by said feeler for determining release of said latch means whereby to permit free swinging of the bar.

21. Switch mechanism for use with conveyer tracks comprising a switch bar pivotally supported at one end to swing in a plane substantially parallel to the plane of the track, releasable latch means associated with the other end of said bar whereby normally to retain it in a position wherein it obstructs free passage of bodies along the track, and means engageable by an element of a body so moving for releasing such latch means.

22. In combination with a conveyer, a movable switch device, a retaining latch

therefor, and means for releasing the latch comprising a feeler carrying arm normally positioned across the path of a body moving along the conveyer but movable independently of the switch device out of such path.

23. Switch mechanism of the class described comprising a movable switch member, a releasable latch for retaining said member in normal position, a link connected 10 to said latch, a feeler member, and means for connecting said feeler member and link whereby to transmit movement from the former to the latter.

24. In a conveyer system having diverging ways along which a series of carriers are conducted, switching mechanism including a movable switch member normally in the path of travel of the carriers and operative 15 through contact with certain of said carriers to cause the switching of the latter car-

riers into one of said ways, but arranged to be moved by other carriers into an inoperative position, and means comprising a movable element, supported independently of said switch member, for determining movement of the latter. 25

25. In a conveyer system having diverging ways for carriers, the combination of a switch normally in position to divert carriers from one of said ways into another, 30 said switch being mounted to be moved out of said position by the carriers, means for locking said switch in its normal position, and mechanism for operating said locking means including a device supported independently of said switch and arranged to be struck by the carriers before they reach said switch. 35

ROBERT AMORY.
